(57) **CLAIM**

The ornamental design for a lighting element for display stand as shown and described.

DESCRIPTION

1. Lighting element for display stand

1.1 : Front perspective

1.2 : Rear perspective

1.3 : Front

1.4 : Back

1.5 : Left

1.6 : Right

1.7 : Top

1.8 : Bottom

1.9 : Reference

Reproduction 1.9 is a reference view showing the state of use with a stand for a display device; the broken lines indicate portions of the article that form no part of the claimed design; the broken lines shown in reproduction 1.9 illustrate environmental structure and form no part of the claimed design.

1 Claim, 9 Drawing Sheets
